UNITED STATES PATENT OFFICE.

ANTHON B. BENSON, OF ST. PAUL, MINNESOTA.

REFRIGERATOR.

1,159,564.

Specification of Letters Patent.

Patented Nov. 9, 1915.

Application filed July 22, 1914. Serial No. 852,414.

To all whom it may concern:

Be it known that I, ANTHON B. BENSON, citizen of the United States, residing at St. Paul, in the county of Ramsey and State of Minnesota, have invented certain new and useful Improvements in Refrigerators; and I do hereby declare the following to be a full, clear, and exact description of the invention, such as will enable others skilled in the art to which it appertains to make and use the same.

My invention relates to refrigerators, and has for its object to improve the same in the several particulars hereinafter noted.

Generally stated, the invention consists of the novel devices and combinations of devices hereinafter described and defined in the claims.

In the accompanying drawings, which illustrate the invention, like characters indicate like parts.

Referring to the drawings, Figure 1 is a vertical section taken through the refrigerator on the line $x^1 x^1$ of Fig. 2; and Fig. 2 is a horizontal section taken on the line $x^2 x^2$ of Fig. 1.

The box or body of the refrigerator may be of any suitable construction, and it is provided with a main door 2, which normally closes an opening into the storage compartment of the refrigerator, and with a door 3 that normally closes an opening into the ice compartment of the refrigerator.

The ice-containing compartment 4 of the refrigerator preferably has its bottom depressed below the bottom of the storage compartment 5, and on this depressed bottom is removably located an ice-supporting table 6, having laterally spaced upper bars 7 and an intermediate lower water-deflecting bar 8.

The numeral 9 indicates a drainage passage which opens through the bottom of the refrigerator from the ice compartment.

The numeral 10 indicates a cake of ice placed on the ice-supporting table.

Extending transversely across the interior of the refrigerator, and partly separating the compartments 4 and 5, is a partition that is made up, preferably, of parallel channel-shape metallic end bars 11, and parallel transversely extended deflecting bars 12, which latter, at their ends, are detachably secured to the flanges of said end bars 11 by small nut-equipped bolts, which make it possible to replace any of the said bars 12, in

case they should be badly bent or broken. However, the said bars 11 and 12 may be connected by rivets, solder, or otherwise, when desired. In cross section, said bars 12 are preferably made approximately Z-shape, with their webs at such angles to their edge flanges that, when the partition is in a vertical position, the webs of the said bars 12 will stand at an angle of approximately forty-five degrees, increasing in a direction from the compartment 5 toward the compartment 4. This arrangement gives the best possible circulation of air between the ice compartment 4 and storage compartment 5.

The partition described is mounted for both pivotal movements and for limited vertical movements, and, as shown, this is accomplished by studs or retaining pins 13 secured on the sides of the refrigerator, and working through longitudinal slots 14 in the webs of the end bars 11. When the partition is in an upright normal position, as shown by full lines in Fig. 1, its lower portion is confined between the ice table and one or more stop lugs or brackets 15, secured on the bottom of the refrigerator on the storage compartment side 5 thereof. The slots 14 are of such length that the partition 85 may be lifted vertically far enough to carry its lower end over the stop lug 15, and also above the top of the ice table. This construction makes it possible, when the ice is removed, or melted to a very small piece, to 90 first lift the partition above the stop 15, and then to turn the same into a horizontal position, indicated by dotted lines in Fig. 1, for the purpose of cleaning the same. The partition could then be turned back to its 95 working position, or it may be inverted or turned upside down into working position. This turning of the partition completely end for end, or upside down, increases the working life of the partition, by providing 100 two sides, either of which may be used in case one side is badly distorted or damaged by the ice. The slats or cross bars 12 of the partition are supported at their ends only by the upright end bars 11 of said partition, 105 so that the entire space between the said bars 12 is unobstructed, or open for the free circulation of air.

The device described is of small cost, may be easily incorporated in various different 110 kinds of ice chests, and is efficient for the purposes had in view.

What I claim is:—

1. In an ice chest having an ice chamber, a partition constructed substantially alike on both vertical faces and mounted for complete pivotal movements, so that it may be set, at will, with either side exposed to the ice chamber.
2. An ice chest having an ice chamber and provided with a partition made up of vertical end bars and horizontal cross slats and constructed substantially alike on both vertical faces, the said partition being mounted for limited vertical and for complete rotary movements so that it may, at will, be turned with either face exposed to the ice chamber, and stop devices on the bottom of the ice chest with which the lower portion of said partition may be engaged and disengaged by vertical sliding movements of said partition.
3. The combination with an ice chest, having an ice table and a stop spaced from said table on the bottom of said chest, of a parti-

tion made up of end bars and horizontal cross slats, the said partition being mounted 25 for limited vertical and for complete rotary movements, the vertical sliding movement thereof, permitting the same to be raised above said stop and ice table, the lower portion of said partition normally being 30 dropped between said table and stop, so that said partition is held against rotation.

4. In an ice chest having an ice chamber, a partition having a multiplicity of air passages and mounted for pivotal movements 35 so that it may be set, at will, with either side exposed to said ice chamber, and devices for locking said partition in an upright position.

In testimony whereof I affix my signature 40 in presence of two witnesses.

ANTHON B. BENSON.
